UNITED STATES PATENT OFFICE.

ALEXANDER T. STEVENSON, OF PORTLAND, OREGON.

MILK-BOTTLE PROTECTOR.

1,186,502.

Specification of Letters Patent.

Patented June 6, 1916.

Application filed April 5, 1915. Serial No. 19,178.

To all whom it may concern:

Be it known that I, ALEXANDER T. STEVENSON, a citizen of the United States, residing at Portland, in the county of Multnomah and State of Oregon, have invented certain new and useful Improvements in Milk-Bottle Protectors, of which the following is a specification.

My invention relates to improvements in milk bottle protectors, and the main object of my invention is the provision of a device for preventing the unlawful taking or stealing of the empty bottle or the full bottle of milk delivered to the household.

Another object of my invention is the provision of a protector or lock which will secure the empty bottle in position and which empty bottle can only be removed when the full bottle is inserted in the device, said insertion also locking the full bottle.

Another object of my invention is the provision of a lock or protector which will absolutely prevent taking of the bottle of milk, which will be small and compact in size and which may be easily applied to the door casing or other convenient support.

Another object of my invention is the provision of a device which will receive and lock the empty bottle and which will receive and lock the full bottle, the said locking of the full bottle releasing the empty bottle, the device being simple and durable in construction, ornamental in appearance and capable of production at such a low price as to make its use desirable and necessary.

With these objects in view my invention consists of a device in the form of a cylindrical casing adapted to receive the neck and mouth of the bottle and having means to engage and lock said neck, said means being concealed by an outer casing.

The invention further consists of a bottle protector or lock embodying novel features of construction and combination of parts substantially as shown, described and particularly defined by the claims.

In order that the detailed construction and operation of my device may be fully understood and its advantages be fully appreciated I have shown in the accompanying drawings a milk bottle protector or lock embodying my invention, it being understood that any changes may be made in the construction which come within the scope of the claims.

Figure 1 represents a side elevation of the

device fastened to a suitable support, or in position for use, the outer casing being shown in section. Fig. 2 represents an elevation of the device taken at a right angle to the position shown in Fig. 1 and showing the locking means in the position they assume when forced outward by the neck and mouth of the bottle. Fig. 3 represents a central sectional view of the device showing how the locking means are forced outward by engagement with the mouth of the bottles, and Fig. 4 represents a top plan view of the device.

Referring by letter to the drawings in which similar letters denote corresponding parts in all the views of the drawings, the letter A designates a suitable support which is preferably the frame work or door casing, B designates angle brackets secured to said support, and C designates an open or tubular casing forming the body or main portion of my device, and provided with the protecting casing C'.

The tubular body portion is open throughout and about the size to admit the mouth D, of the bottle E, such as is common for containing milk or cream, and the body is provided preferably with the four sets of vertically disposed slots or openings F, and with the four series of double flat spring plates G, which have their outer ends H, rigidly secured to the body portion, and their inner free ends J, loosely hinged to permit the springs to move outward as shown in Figs. 2 and 3 when the neck of the bottle engages the locking lugs or keepers K, carried in pairs by each set of double spring plates G, said lugs moving in and out and guided by slots F. From this construction it will be apparent that the tubular body portion provides a receiver in which is inserted the neck of the full or empty bottle, and that said neck of the full bottle engages and forces the locking lugs outward releasing the mouth of the empty bottle, permitting its removal and simultaneously locking the mouth of the full bottle and to insure the proper operation of the locking lugs or keepers I attach to the outer face of two of the springs, the curved plates L, formed at their ends with openings L', and to two of the other spring members the pair of shorter curved plates M, provided with pins M' for engaging the openings L' of said plates L, thus locking said curved plates and at the same time retaining

the springs with their locking lugs in proper position.

From the foregoing description the operation of my device will be readily understood, and it will be apparent that the empty bottle is inserted in the receiver mouth downward, which mouth portion forces the locking lugs outward until the mouth portion passes the upper set of lugs and as soon as passed the mouth portion is secured between the locking lugs, as shown in dotted lines in Fig. 3 locking the empty bottle in the receiver. The mouth of the full bottle is inserted in the lower portion of the receiver forcing the locking lugs from engagement with the mouth of the empty bottle allowing the removal of said empty bottle, and upon its removal the said locking lugs instantly are sprung inward and engage the mouth of the full bottle.

It will be noted by the dotted lines in Fig. 3 that two sets of the locking lugs K', are shorter than the other sets of locking lugs K, the purpose of which is to cause one set of lugs to open in advance or to a greater extent than the other set which insures the proper entrance and removal of the bottles and the proper locking of said bottles by the action of insertion and removal. The longer locking lugs K, secured to the flat spring plates G carrying the shorter curved plates M, are first engaged by the bottle and lifted sufficiently to allow the pins M' to clear the openings L' before coming into engagement with the shorter lugs K', thus unlocking the plates L. Then when the bottle has been pushed past the lugs K and K', they will spring in and the curved plates M will again lock the plates L by reason of the pins M' entering the opening L', thus locking the lugs K'. It will also be noted that the locking mechanism is entirely concealed and protected by the outer covering, which gives an attractive exterior appearance to the device. This covering and receiver may be of any shape and may be made of any desired material and it might be desirable to make the ends of the receiver flaring instead of straight.

From the description and drawings the advantages of my invention will be readily understood and it will be at once apparent that I provide a simple, inexpensive and practical device which can only be operated by the proper person and which will prevent the stealing of the empty bottle or the full bottle of milk or cream from households and which will present an attractive and ornamental appearance.

I claim:

1. A lock or protector of the character described, consisting of an open ended receiver to permit the insertion of the mouth of an empty bottle and a full bottle, and locking means engaging the mouth portion

of either of said bottles to secure the empty or full bottle in the receiver, said locking means consisting of a pair of curved plates and a pair of shorter curved plates having lugs to engage the mouth of the bottle.

2. A lock or protector of the character described, consisting of an open ended receiver to permit the insertion of the mouth of an empty bottle and a full bottle, and locking means engaging the mouth portion of either of said bottles to secure the empty or full bottle in the receiver, said locking means consisting of a series of spring plates having lugs to engage the mouth of the bottle, and means for retaining the spring plates and lugs in locked position, said means consisting of a pair of curved plates and a pair of shorter curved plates, openings in said curved plates and pins secured on said shorter curved plates to engage the said openings.

3. A lock or protector of the character described, consisting of an open ended receiver to permit the insertion of the mouth of an empty bottle and a full bottle, and locking means operated by said insertion to lock the empty or full bottle in the receiver, said means consisting of a pair of curved plates and a pair of shorter curved plates, openings in said curved plates and pins secured on said shorter curved plates to engage the said openings, said means being protected and concealed by an outer casing.

4. A lock or protector of the character described, consisting of an open ended receiver to permit the insertion of the mouth of an empty bottle and a full bottle, and locking means mounted in said receiver and acting to release one bottle and lock the inserted bottle, said locking means consisting of a pair of lugs carried by a pair of flat springs carrying curved plates and a pair of longer lugs carried by a pair of flat springs carrying a pair of shorter curved plates, said shorter curved plates carrying pins to engage openings in said curved plates.

5. A lock or protector of the character described, consisting of an open ended receiver to permit the insertion of the mouth of an empty bottle and a full bottle and locking means consisting of a series of pairs of lugs operated by said insertion to engage the flange around the mouth of the bottle to lock the empty or full bottle in the receiver, said means being protected and concealed by an outer casing.

6. A lock or protector of the character described, consisting of an open ended receiver to permit the insertion of the mouth of an empty bottle and a full bottle and locking means mounted in said receiver and acting to release one bottle and lock the inserted bottle, said means consisting of a series of pairs of spring actuated locking lugs

adapted to engage the flange around the mouth of the bottle.

7. A protector for milk bottles, consisting of an open ended container to receive the flanged mouth of an empty bottle and a full bottle of milk, a series of lugs arranged in pairs to engage the flanged mouth of the bottle, and connections between the pairs of lugs whereby the insertion of the flanged mouth of the full bottle releases the lugs

from the flanged mouth of the empty bottle to release said empty bottle and lock the full bottle.

In testimony whereof I affix my signature in presence of two witnesses.

ALEXANDER T. STEVENSON.
